UNITED STATES PATENT OFFICE.

HERBERT EDWARD SHREEVE, OF MILBURN, NEW JERSEY, ASSIGNOR TO WESTERN ELECTRIC COMPANY, OF NEW YORK, N. Y., A CORPORATION OF ILLINOIS.

TELEPHONIC DEVICE.

1,159,603.

Specification of Letters Patent.

Patented Nov. 9, 1915.

Application filed February 17, 1914. Serial No. 819,256.

To all whom it may concern:

Be it known that I, HERBERT EDWARD SHREEVE, a subject of the King of Great Britain, residing at Milburn, in the county 5 of Essex and State of New Jersey, have invented a certain new and useful Improvement in Telephonic Devices, of which the following is a full, clear, concise, and exact description.

10 This invention relates to telephonic devices and more particularly to microphonic devices in which the intimacy of contact of the material composing the resistance varying medium varies.

15 The object of this invention is to provide means for automatically regulating or controlling the intimacy of contact of the material of the resistance varying medium of such device to obtain the most beneficial results.

20 In accordance with this invention, a differentially wound electromagnet is provided in operative relation to the microphonic device. Means are provided whereby 25 an increase or decrease of resistance of the resistance varying medium controls the flow of current through the differential windings of the electromagnet, causing said electromagnet to react upon the microphonic 30 device to control the contact relation of the resistance varying medium.

25 For a more complete understanding of this invention, reference may be had to the accompanying drawings, wherein—

35 Figure 1 is a skeleton view of a transmitter embodying this invention, and Fig. 2 is a skeleton view of a repeater embodying this invention.

40 As shown in Fig. 1, the transmitter may be of the usual granular carbon type having a granular carbon transmitter button composed of an externally threaded cylindrical member 10, across the open ends of which are flexible members 11 and 12 held in place 45 by means of internally threaded clamping rings 13 and 14 which engage said threaded member 10. The member 11 forms the back electrode of the transmitter. Granular carbon 9 forming the resistance varying medium 50 is contained within the chamber just described. To the member 12 is secured a front electrode 15 having an outwardly extending stem 16, the end of which is in contact with a diaphragm 17. The stem 16 55 is provided with a shoulder 18 against which

rests one end of a spring 19, which insures proper contact being maintained between said stem 16 and said diaphragm 17. 20 represents the usual transmitter mouthpiece. The foregoing description applies to one 60 form of an ordinary carbon button transmitter which, for convenience, has been used in connection with the illustrating of one form of this invention. The invention herein embodied will now be described in 65 detail.

To the member 11 is secured a pole piece 30 which coöperates with a core 31 of an electromagnet. The pole piece 30 and the core 31 are provided with windings 32 and 70 33. These windings are opposed, 32 being in shunt with the resistance varying medium 9 of the transmitter, and the windings 33 being in series therewith. One terminal of the winding 33 is connected to the back electrode 75 11 and the other leads through an impedance coil 34 to one side of battery 35. The other side of battery 35 may be connected to the diaphragm 17 through an induction coil primary 36, secondary winding 37 of which is 80 connected with a telephone line. One terminal of the winding 32 is connected to the back electrode 11 and the other may be connected through an impedance coil 38 to the diaphragm 17. The impedance coils 34 and 85 38 are in series with the windings 33 and 32 respectively, in order to prevent the passage of alternating currents through said windings. A path for alternating currents is provided through a condenser 39, which shunts 90 the windings 32 and 33 and the impedance coils 34 and 38.

In microphonic elements, it has been determined that the resistance of the resistance varying medium varies between very 95 wide limits. When the resistance is at the lower limit, the medium is said to be in a "packed" condition, whereas when at the upper limit, it is said to be in an "over sensitive" condition. Now, it has furthermore 100 been determined that the efficiency of a microphonic element is greatly increased if the fluctuations of the resistance of the resistance varying medium be confined to closer limits. By the use of this invention, this result is accomplished with the accompanying increased efficiency of the element.

With current flowing through the microphonic element, there may be an increase or decrease of resistance of the resistance vary- 110

ing medium depending upon the condition of said medium. Assuming that an increase in resistance results, there is immediately an increased flow of current through the shunt winding 32 and a decreased flow 5 through the medium 9 and the series winding 33, which, due to said windings being opposed, react upon the member 11 to move said member inwardly, thereby increasing the pressure on the resistance varying medium 9. Increase of pressure on said medium 9 causes the resistance of said medium to be decreased. Should there be a decrease of resistance of said medium, there would 10 follow a decreased flow of current through the shunt winding 32 and an increased flow through said medium and the series winding 33. This would necessarily result in the pull on the member 11 being increased, allowing said member to move outwardly and 15 to decrease the pressure on the medium 9. Decreasing the pressure on said medium causes an increase of the resistance thereof. It will be seen, therefore, that when there 20 is a tendency for the resistance of the resistance varying medium 9 to either increase or decrease, there is an immediate reapportionment of current through the shunt and series windings 32 and 33, causing a reaction 25 upon the member 11. In this way the resistance of the resistance varying medium 9 is controlled by regulating or controlling the intimacy of contact of the material of which said medium is composed.

30 Referring to Fig. 2 which illustrates a repeater embodying this invention, 50 represents resistance varying medium, and 51 and 52, respectively, represent front and back electrodes of a microphonic or transmitting element of the repeater. Secured to the electrode 52 is a pole piece 53 which cooperates with a core 54 of the receiving element of the repeater. A receiving winding 55 of the repeater is wound over the core 54 and the pole piece 53, and is in series with an induction coil secondary 56, the primary 57 of which is in the incoming telephone line. The repeater is provided with a local transmitter circuit comprising the front 40 electrode 51, the resistance varying medium 50, the back electrode 52, a condenser 58 and an induction coil primary 59, the secondary 60 of which is in the outgoing telephone line. One terminal of the induction coil 45 primary 59 is also connected to one side of a battery 65, the other side of which is grounded. The core 54 also carries a winding 66, which is in series with the resistance varying medium 50, and a winding 67 in 50 shunt with said medium. In order to prevent the flow of alternating current through the series winding 66, an impedance coil 68 is placed in series therewith, and for like purpose an impedance coil 69 is placed in series 55 with the shunt winding 67. In order to ini-

tially regulate the flow of current from battery 65, through the resistance varying medium 50, shunt winding 67 and series winding 66, a variable resistance 70 is placed in series therewith.

It will be seen that the intimacy of contact of the material of which the resistance varying medium 50 is composed is controlled in the same manner as is that of the resistance varying medium 9 of Fig. 1. It 75 has been determined that the efficiency of the microphonic element may be still further increased by placing a resistance 71, having a negative temperature coefficient in series with the shunt winding of the device. 80 This resistance 71 has such characteristics that upon an increase in current therethrough the resistance is reduced, thereby permitting a greater flow of current and an increased pull on the electrode of the transmitting element. With a decrease of current through this resistance 71, there is an increase of resistance, resulting in a reduction of current through the circuit and a decreased pull on the electrode of the transmitting element. It is obvious that said resistance 71 may be readily included in series with the shunt winding 32 of Fig. 1.

What is claimed is:

1. In a telephonic device, a microphonic element, an electromagnet in operative relation thereto, and a magnetizing circuit for said electromagnet including a winding in series with, and a winding in shunt with said microphonic element.
2. In a telephonic device, a microphonic element, an electromagnet controlling the operation of said element, and differential magnetizing windings for said electromagnet and in circuit with said microphonic element.
3. In a telephonic device, a granular microphonic element, and an electromagnet having differential magnetizing windings thereon in circuit with and in operative relation to said element, said windings coöperating upon a flow of current therethrough to relieve the pressure on the granules of said element upon a tendency thereof to pack.
4. In a telephonic device, a microphonic element, resistance varying material therein, and an electromagnet having differential magnetizing windings thereon in circuit with and in operative relation to said element, said windings coöperating upon a flow of current therethrough to regulate the contact relation of said resistance varying material.
5. In a telephonic device, a microphonic element having relatively movable electrodes therein, resistance varying material between said electrodes, a source of current, and an electromagnet controlling the movement of one of said electrodes, said electro-

magnet having differential windings thereon in circuit with said microphonic element and said source of current.

6. In a telephonic device, a microphonic element, an electromagnet in operative relation thereto, a magnetizing circuit for said electromagnet including a winding in series with and a winding in shunt with said microphonic element, and a resistance having a negative temperature coefficient in series with said shunt winding.

7. In a telephonic device, a granular microphonic element, an electromagnet in operative relation thereto and magnetizing windings for said electromagnet in circuit with said element, one being in series with and another in shunt with said element, said series and shunt magnetizing windings co-operating upon a flow of current therethrough and acting through said element to relieve the pressure on the granules of said element upon a tendency thereof to pack.

8. In a telephonic device, a granular microphonic element, an electromagnet in operative relation thereto, magnetizing windings for said electromagnet in circuit with said element, one being in series with and another in shunt with said element, and a resistance having a negative temperature coefficient in series with said shunt winding, said series and shunt magnetizing windings and said resistance co-operating upon a flow of current therethrough and acting through said electromagnet to relieve the pressure on the granules of said element upon a tendency thereof to pack.

9. In a telephonic device, a granular microphonic element, a vibrating electrode for said element, an electromagnet in operative relation thereto, and differential magnetizing windings for said electromagnet in cir-

cuit with said element, said differential windings co-operating upon a flow of current therethrough and acting upon said electromagnet to cause said electrode to move outward upon a decrease of resistance of said microphonic element.

10. In a telephonic device, a granular microphonic element, a vibrating electrode for said element, an electromagnet in operative relation thereto, and differential magnetizing windings for said electromagnet in circuit with said element, said differential windings co-operating upon a flow of current therethrough and acting upon said electromagnet to cause said electrode to move inwardly upon an increase of resistance of said microphonic element.

11. In a telephonic device, a granular microphonic element, an electromagnet in operative relation thereto and having differential magnetizing windings in circuit with said element, said differential magnetizing windings co-operating upon a flow of current therethrough and acting through said electromagnet to maintain a proper contact relation between the granules of said element.

12. In a telephonic device, a transmitting element, an electromagnet controlling the operation of said element, and differential magnetizing windings for said electromagnet and in circuit with said transmitting element.

In witness whereof, I hereunto subscribe my name this 14th day of February, A. D. 1914.

HERBERT EDWARD SHREEVE.
